ATTORNEY

UNITED STATES PATENT OFFICE.

MAGDALENA ZIEROLD, OF WILKINSBURG, PENNSYLVANIA.

HAT-FASTENER.

1,250,264.

Specification of Letters Patent. Patented Dec. 18, 1917.

Application filed April 23, 1917. Serial No. 164,019.

To all whom it may concern:

Be it known that I, MAGDALENA ZIEROLD, a citizen of the United States, residing at Wilkinsburg, in the county of Allegheny and State of Pennsylvania, have invented certain new and useful Improvements in Hat-Fasteners, of which the following is a specification.

This invention relates to hat fasteners, and 10 more particularly to that type which are permanently attached to the hat.

The object of the invention is to provide a simply constructed, ornamental and convenient device of this character which will 15 effectively connect the hat to the hair of the wearer and which, when once applied to a hat, will remain in position during the life of the hat, if desired.

Another object is to construct a fastener 20 of this character which may be positioned out of the way during the adjustment of the hat on the head of the wearer and hence will not interfere with the proper fitting of the hat.

25 With the foregoing and other objects in view, which will appear as the description proceeds, the invention resides in the combination and arrangement of parts and in the details of construction hereinafter described 30 and claimed, it being understood that changes in the precise embodiment of the invention herein disclosed may be made within the scope of what is claimed without departing from the spirit of the invention.

35 In the accompanying drawings:—

Figure 1 represents a horizontal section through a portion of a hat showing this improved fastener applied and in plan,

40 Fig. 2 is a detail vertical section through a hat crown and brim with this fastener shown in side elevation applied, the hair gripping portion thereof being shown raised into inoperative position in dotted lines, and

45 Fig. 3 is a longitudinal horizontal section through the fastener with the jaws shown closed in full lines and open in dotted lines.

In the embodiment illustrated, the hat fastener constituting this invention is shown applied to a hat H, being mounted in an 50 opening O formed in one side of the crown thereof.

This fastener comprises a pair of oppositely curved hair gripping jaws 1 and 2 having handles 3 and 4 extending rearwardly therefrom and pivotally connected 55 as shown at 5. These handles 3 and 4 are

preferably constructed of sheet metal substantially U-shaped in cross section and opening toward each other, the flanges or sides of said handles increasing in width 60 toward their pivoted ends and shown arranged inlapping relation in Fig. 1 forming a housing in which is mounted a spring 6 coiled around a pintle 5 and having its opposite ends engaging the inner faces of the 65 two handles 3 and 4, (see clearly Fig. 3). This spring tends to force the handles normally outward and the gripping jaws 1 and 2 inward toward each other and thereby hold them in closed operative position such as they 70 will assume when engaged with the wearer's hair. These jaws 1 and 2 are preferably made comparatively wide at their gripping ends to enable them to obtain a substantial grip on the hair and prevent them from becoming entangled with the hair. These jaws 75 are hingedly connected at their inner ends with the handles 3 and 4 as shown at 7 and are designed to swing upwardly into the dotted line position shown in Fig. 2 when 80 the hat is to be placed on the head of the wearer and after it has been so placed, the handles 3 and 4 are gripped and moved slightly outward in the opening O which causes the jaws to swing downwardly into 85 horizontal position and then the slight pressure on the handles 3 and 4 moving them toward each other causes said jaws to separate and when released, owing to the action of the spring 6 to automatically close and effectively grip the hair of the wearer thereby 90 securely holding the hat in position.

While one of these fasteners only is shown and described, it is to be understood that two of them are employed arranged at diametrically opposite points on the hat.

Any suitable ornaments may be mounted in the free ends of the handles 3 and 4, artificial roses 8 being here shown although they need not necessarily be used, it being obvious 100 that stones or any other desired ornaments may be employed.

In the application of this device, the handles 3 and 4 are pressed toward each other into the dotted line position shown in Fig. 3, 105 and are inserted from the inside of the hat through the opening O until the fastener is brought into the position shown in Fig. 1 and when in this position the ornaments 8 may be applied to the free ends of the handles and the device is then ready for use.

From the foregoing description, taken in

connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:

1. A hat fastener comprising a pair of connected jaws and handles pivotally connected with each other, the jaws being hinged to swing in a plane at right angles to the plane of their pivotal movement.
2. A hat fastener of the class described comprising a pair of outwardly bowed jaws

having comparatively wide gripping ends, handles connected with the rear ends of said jaws and pivotally connected adjacent the rear ends of the jaws, said handles being U-shaped in cross section and arranged with their open portions toward each other forming a housing between them, a pintle connecting said handles at their inner ends, a spring coiled on said pintle within said handles with its opposite ends engaging the inner faces of said handles at points in advance of said pintle, and a hinge formed between said jaws and handles.

In testimony whereof I affix my signature in presence of two witnesses.

MAGDALENA ZIEROLD.
